UNITED STATES PATENT OFFICE

ALBERT W. METZNER, OF DAYTON, OHIO, ASSIGNOR, BY MESNE ASSIGNMENTS, TO THE
STANDARD REGISTER COMPANY

MANIFOLDING MACHINE

Application filed October 31, 1924. Serial No. 747,101.

My invention relates to manifolding machines, particularly of the type in which autographic impressions are made on strips of paper fed over a support, and in which the mechanism is formed as a unit which is enclosed by a cabinet that comes down around the entire mechanism except for such clearances as are necessary.

In my application for patent, Serial No. 10 708,790, filed April 24th, 1924, I show and describe a structure of similar nature to the one forming the basis of this application, and on which the present application is an improvement.

15 Among other objects of the present invention is the provision of a cabinet type of manifolder of the character noted, in which the pressure bar, that maintains the paper lightly on the pins during feeding and clamps it 20 tightly when the feed is idle, is fully available at all times.

It is my object in such a machine to provide for a suitable removable writing support for the paper, and for a fixed guide and 25 support for the paper with relation to the feeding devices. It is my object to provide for the rewinding of a record strip, and to provide means which will guide, and maintain the strip in smooth condition, while at 30 the same time not interfering with full freedom of action of the pressure bar, and easy removal of the cabinet.

These objects and other advantages to be noted, I accomplish by that certain construction and arrangement of parts to be hereinafter more specifically pointed out and claimed.

In the drawings:

Figure 1 is a top plan view of the device.

40 Figure 2 is a side elevation broken away to show a rewind device.

Figure 3 is a plan view and projected edge-wise elevation of the deflector plate.

45 Figure 4 is a detail plan view of the projection of the enclosing cabinet at the issue orifice therein. Figure 4^a is a perspective view of the pressure bar device.

50 Figure 5 is a side elevation of the device with the rewind parts omitted, and the cabinet broken away.

Figure 6 is a plan view of the paper support plate.

Figure 7 is a plan view of the issue end of the writing support.

The machine is built on a base 1, on which 55 are erected side frames 2, between which are supported the paper rolls 3. A cabinet 4 is arranged so as to enclose the entire structure except for the writing table, a mouth at the issue portion of the machine, and such openings as are necessary for the feed shaft, stop pins and the like. No particular illustration is made of the sides of the cabinet, as this portion of the cabinet is not a part of the present invention.

60 The feed shaft of the machine, shown at 5, is supported in the side frames, and carries the feed pin wheels 6, and the pressure bar control cams 7. Mounted in the top of the side frames above the feed shaft is a plate 70 8, which forms the feed portion of the paper support. This plate has a central rib 9, for antifriction purposes, and a pair of lengthwise slots 10, 10 for feed pin clearance. It 75 is curved down at the one side, to form a support for a rewound paper strip, and has four lugs 11, through which are mounted suitable screws for holding the plate in place in the frames.

I am not aware of any one in the past having mounted a plate beneath the pressure bar, and about the feed pins in a pin feed register, in which the plate is permanently secured in place, as normally this is part of the writing support, which must be removable to 85 get at the paper. It should be noted that the rewind device of my machine is located well forward of the machine as to avoid the necessity of removing the plate 8 to get at the 90 rewind.

The other portion of the writing table, as indicated at 12, may be removably or hingedly mounted in the frame of the machine, and preferably it will rest when in operative 95 position on the two nearest lugs of the plate 8. The plate 8 and the forward end of the writing table are cut at 13, and 13^a, so as to fit into each other. The carbon paper clamp device (not shown) is secured to the finger 100

14 on the one end of the writing support plate.

The pressure bar device is in the form of a plate of metal 15, beaded to provide an antifrictional surface, as at 16, to correspond with the bead or ridge on the plate 8. This plate is secured to a pair of arms 17, mounted in the frame forwardly of the feed shaft, and to rock the bar out of the way, these arms are 10 swung upwardly, as is familiar practice in the art, for pressure rollers.

The cams 7 on the feed shaft, which are of the type shown and used in the patent to T. F. Schirmer, No. 940,481, dated November 16, 15 1909, are cleared by the cut in side edges 8^a of the plate 8. The pressure bar has a pair of small rollers 18 thereon which engage on these cams, to the end that the pressure bar is kept in position lifted away from the plate 8, except at the end of each feeding cycle, when it will drop and clamp the paper against being shifted about in writing upon it or carrying the machine around. Suitable spring means and latches for the pressure bar to hold 20 it up against spring tension and out of operation are found in all devices of this character and no illustration of them is shown in my drawings, as this structure is well known except for the particular nature of the bar 25 which is shown in my patent application heretofore referred to.

The opening in the cover or cabinet may be a single one, having a portion 20 which exposes the paper for writing thereon, and a 30 widened portion 21, which leaves a space for the pressure bar to come to operative position, and two slots 22, for clearance of the arms that support the pressure bar, so that this member can be swung up and dropped 35 back into place without disarranging the cabinet.

The portion lying between the two slots 22, and defining the forward wall of the opening in the top of the cabinet, is curved as at 40 23, and punched out at 24, 24, to receive the hinge tongues 25, 25, on a gravity guide plate 26. This plate 26 is formed, as indicated in Figure 1 so as to come to a position beneath, but not necessarily engaged by the pressure 45 bar, and the hinging is provided so that the pressure of this plate is not heavy, and also so that the cabinet can be lifted up and replaced, without disarranging the pressure bar in any way.

50 I have indicated in dotted lines in Figure 2 a rewind device for manifolding registers, and have generally indicated this mechanism by the letter A. The rewind roll itself is indicated at 27, and the web of paper rewound 55 on this roll after it passes through the feed devices, is indicated at 28. The webs of paper being fed from the machine are indicated at 29.

As so constructed the rolls of paper are 60 mounted in the machine and brought up and

over the writing table, which is dropped into position after the rolls have been set in place. The feed shaft is brought to initial position, and the webs of paper are collected and set over the pins, whereupon the pressure bar is dropped from its position in Figure 5 to its position in Figure 2. Carbon paper when used is placed between the several webs and the record web being the lowermost one, is brought down around the plate 8 and affixed to the rewind roll.

The cabinet is then set over the mechanism, and the plate 26 is set between the record web and the webs to be issued from the machine. The feed handle may then be revolved which 70 will draw the webs of paper along over the writing table, with the record strip being given an enforced path down toward the rewind roll.

The closeness of the free edge of the plate 85 26 to the delivery point of the paper from the feed pins, is such that this web of paper cannot fail to be fed away from the other webs, and cannot ball up and clog the machine. This is particularly valuable where the rewind feed does not operate together with the feed pins but merely revolves enough to take up slack in the record web during portions 90 only of the feed pin operation.

Should the writing table get twisted out 95 of shape, or seat improperly for various reasons, which we find takes place in these machines, this will not make any difference as to the exactness of the relation of the paper support with relation to the feed pin wheels, 100 pressure bar, cams and the like. It is highly essential that no drag be given to the paper webs while they are being fed, as this results in impeding the shifting of the webs with relation to the pins, and the aligning action 105 of the pins cannot properly function. The fixed paper support thus assures against the deflections of prior machines to the end of avoiding improper feed, or clamping action.

The use of a bead or ridge on the paper support, co-operating with a bead or ridge on the pressure bar, results in an antifriction contact with both of said rigid elements with the paper, so that while the pressure bar will hold the paper on the pins, it will not exert pressure on the paper except at the periods when the cams permit the bar to drop, and the shape of the ridges being rounded will permit the paper to slip or slide easily through the opening between the plate 8 and the bar.

Having thus described my invention, what I claim as new and desire to secure by Letters Patent, is:—

1. In combination in a manifolding machine, a frame, a pin wheel for feeding paper 125 strips from said frame, a plate for holding said paper strips and having clearance for the pins on said wheels, and a plate for holding the paper down onto the pins, both of said plates having a bead lengthwise there- 130

of, and hence crosswise of the machine between which the paper is passed, for an antifriction engagement with the paper.

2. In combination in a manifolding machine, a frame, a pin wheel for feeding paper strips from said frame, a plate for holding said paper strips and having clearance for the pins on said wheels, and a plate for holding the paper down onto the pins, both of said plates having a bead lengthwise thereof, and hence crosswise of the machine between which the paper is passed, for an antifriction engagement with the paper, and means for holding the second named plate away from binding contact with the paper on the first named plate, when the feed device is in operation.

3. In combination in a manifolding machine, a frame, a pin wheel for feeding paper strips from said frame, a paper support having clearance for the said pin wheel and having a longitudinal bead, means for permanently securing the support in place, in the frame, a writing support mounted in the frame for supporting paper prior to reaching the feed so as to take written impressions, and a pressure element for holding the paper down on the pins.

4. In a manifolding machine having a framework, a base, paper supporting and feeding mechanism including a rewind mechanism in said framework, and a cover for said framework having an opening exposing the paper support beyond the feeding mechanism, deflecting means adapted to rest by gravity on the paper webs for separating webs to be rewound and webs to be issued by the feeding mechanism, said means movably secured to said cover beyond the feeding mechanism, and lying within the aforesaid opening.

5. In a manifolding machine having a framework, a base, paper supporting and feeding mechanism including a rewind mechanism in said framework, and a cover for said framework having an opening exposing the paper support beyond the feeding mechanism, deflecting means adapted to rest by gravity on the paper webs for separating webs to be rewound and webs to be issued by the feeding mechanism, said means movably secured to said cover beyond the feeding mechanism, said deflecting means comprising a plate hinged to a portion of said cover defining said opening, and lying within said opening.

6. In a manifolding machine having a framework and paper supporting and feeding mechanism including a rewind mechanism in said framework, and a cover for said framework having an opening exposing the paper support beyond the feeding mechanism, deflecting means adapted to rest on the paper webs for separating webs to be rewound and webs to be issued by the

feeding mechanism, said means movably secured to said cover beyond the feeding mechanism, and said machine having a pressure element secured to the framework and extending across the machine and cooperating with the feeding mechanism, and said deflecting means having a free edge beneath said pressure element.

7. In a manifolding machine having a framework and paper supporting and feeding mechanism including a rewind mechanism, a pressure element hingedly mounted on the frame shaped to extend down over the paper in cooperation with the feeding mechanism, and a cabinet enclosing said framework and having an opening to expose the paper support and the pressure element, a deflector hinged on a portion of said cabinet defining said opening and ahead of said paper feeding mechanism, said deflector adapted to lie between the paper webs to be retained in the machine after feeding and those to be issued from the machine.

8. In a manifolding machine having a frame and a pin wheel for feeding paper strips from said frame, a paper support having clearance for said pin wheel, means for permanently securing the said support in place, a writing support mounted on the frame for supporting paper prior to reaching the feed so as to take written impressions, and a pressure element for holding down the paper on the pins without clamping it against the paper support during the feeding, a cabinet adapted to enclose said frame, said cabinet having an opening clearing the several supports and said pressure element, said cabinet also having a hinged plate on the forward wall of said opening, said plate positioned to rest on the paper support when the cabinet is in place.
